Charles C. Gill

UNITED STATES PATENT OFFICE.

JOHN FRANK, OF BROOKLYN, NEW YORK.

SHOE AND THE LIKE.

1,116,051.

Specification of Letters Patent.

Patented Nov. 3, 1914.

Application filed July 20, 1914. Serial No. 851,848.

To all whom it may concern:

Be it known that I, JOHN FRANK, a citizen of the United States, and a resident of Brooklyn, in the county of Kings and State 5 of New York, have invented certain new and useful Improvements in Shoes and the like, of which the following is a specification.

The invention pertains more particularly 10 to novel means for fastening shoes upon the foot of the wearer, the use of the well-known buttons and shoe strings being avoided.

My invention is particularly adapted as 15 a substitute for the usual button and button-holes on shoes, and its purpose is to avoid the inconvenience due to the use of ordinary buttons and button-holes and to provide fastening means which are readily 20 adjustable to the foot, no inconvenience being experienced at any time in tightening or loosening the shoe upon the foot.

My invention is adapted for use on what 25 are commonly called high shoes and also on low shoes, and in the accompanying drawings I illustrate the same as applied to both characters of shoes.

In carrying out my invention I provide 30 on one flap of the shoe a series of permanently attached knobs or fastenings and on the other flap of the shoe a series of tongues on which are strung buckles adapted to be adjusted along the tongues and clasped thereto at any desired point, said 35 buckles comprising two hinged together members, the bottom one being formed with an opening to engage a fastener on the opposite flap of the shoe and the outer member of the buckle preferably being of ornamental 40 character and adapted when closed down against the tongue on which it is strung, to effect the locking of the buckle to the tongue. The adjustment of the buckle along the tongues permits of the shoe being 45 applied to the foot as tightly or loosely as may be deemed to be comfortable. For high shoes there will be a series of the tongues and buckles provided, and for low shoes one tongue and buckle will prove to 50 be sufficient. In any event the buckles should be of attractive character, because it is one of my purposes that the buckles shall add to the attractive appearance of the shoe.

The invention will be fully understood

from the detailed description hereinafter 55 presented, reference being had to the accompanying drawings, in which:

Figure 1 is a perspective view of a shoe embodying my invention; Fig. 2 is a corresponding view of a low-cut shoe embodying 60 my invention; Fig. 3 is a detached view of a portion of the shoe shown in Fig. 1, the fastener on one flap of the shoe being shown and the tongue on the other flap of the shoe with the outer member of the buckle being 65 turned over against the body of the shoe so as to expose the lower member of the buckle ready to be placed upon the said fastener; Fig. 4 is a sectional view on the dotted line 4-4 of Fig. 3 of the parts shown in Fig. 3; 70 Fig. 5 is a view corresponding with Fig. 4 but showing the parts as having been fastened together and the buckle and tongue having been turned to their proper position for use, and Fig. 6 is a detached perspective view of one of the buckles shown in its open position.

In the drawings 10 designates a high shoe of usual character with the exception 80 of the features constituting my invention provided thereon.

11 denotes one side or flap and 12 the other side or flap of the upper of the shoe 10, and the flap 11 is, in accordance with my invention, provided along its outer edge 85 with a series of fasteners or heads or hooks 14 of the kind, preferably, employed on gloves, plackets and the like. The fasteners 14 may be permanently applied to the flap of the shoe since in accordance with my in- 90 vention it will not be necessary to shift the same in adjusting the shoe to the foot. The flap 12 is formed with a series of tongues 15 which extend over upon the flap 11 and are each provided with a buckle 16 comprising 95 a lower member 17 which is concealed by the tongue 15 and an outer member 18 which may be of any suitable outline but is preferably of ornamental character. The lower member 17 of each buckle is provided with 100 an eye 19 to hook upon the fastener 14, and at its inner edge said lower member 17 is provided with a serrated flange 20. The outer member 18 of the buckle is secured in a hinged manner by pintles 21 to the lower 105 member 17. The tongues 15 are threaded between the members 18, 17 of the buckles and lie upon the serrated edge 20 of the

lower member 17. The buckles may be freely adjusted along the tongues 15 when the upper member of the buckles is turned upwardly in a direction from the outer end 5 of the lower member of the buckles. The buckles are not, therefore, permanently fastened to the tongues 15, and the owner of shoes equipped with my invention may have several sets of the buckles and wear different 10 sets from time to time as occasion might seem to render desirable.

In the use of my invention when the shoe is placed upon the foot the buckles 16 will be loosened on the tongues 15 and the lower member 17 of the buckles will one after another be hooked upon the fastener 14 provided for it, and thereupon the tongue will be drawn tightly through the buckle and the outer member of the buckle turned over 20 against the tongue, this having the effect of causing the material of the tongue to be pinched between the inner surface of the member 18 and the serrated flange 20 of the member 17, the result being that the tongue 25 will be firmly held, the outer member of the buckle exposed and the inner or lower member of the buckle concealed. The buckles 16 are all independently adjustable on the tongues 15, and hence the shoe may be 30 drawn to fit the foot of the wearer with entire convenience.

My invention dispenses with the formation of button-holes in the flap 12 and the sewing of buttons upon the flap 11, and particularly dispenses with the inconvenience of having to remove, adjust and replace the buttons on button-shoes of the usual kind. In accordance with my invention the fasteners 14 remain in permanent position, and 40 the adjustment of the shoe to the foot is made by the buckles and tongues each time the shoe is placed on the foot.

In Fig. 2 I illustrate a low-cut shoe having a strap 22 which will be provided with 45 one of the fasteners 14, and a tongue 23 having one of the buckles 16 thereon, the fastening features shown in Fig. 2 being identical with those shown in Fig. 1 with the exception that in view of the character of 50 the shoe a strap 22 is provided instead of a side or flap 11, such as shown in Fig. 1.

I prefer whenever possible to form the tongues 11 integrally with the section 12 of the shoe, since when said tongues are integral with the material of the section 12, 55 they present a better appearance and are in no danger of becoming detached, the appearance of the entire shoe being improved when the tongues 15 are integral with the upper of the shoe.

What I claim as my invention and desire to secure by Letters Patent, is:

1. A shoe having sections to be closed upon the foot, one of said sections having a fastener-member and the other a tongue and 65 buckle thereon, said buckle being adjustable on the tongue and comprising foldable members adapted when closed toward each other to bind the tongue, and the inner member of the buckle having an eye to engage said 70 fastener-member.

2. A shoe having sections to be closed upon the foot, one of said sections having along its edge a series of spaced apart fastener-members and the other a corresponding 75 series of tongues each with a buckle thereon, said buckles each being adjustable on its tongue and comprising foldable members adapted when closed toward each other to bind the tongue and the inner member of 80 each buckle having an eye to engage one of the fastener-members.

3. A shoe having sections to be closed upon the foot, one of said sections having along its edge a series of spaced apart 85 fastener-members and the other having integrally therewith a corresponding series of tongues each with a buckle thereon, said buckles each being adjustable on its tongue and comprising foldable members adapted 90 when closed toward each other to bind the tongue and the inner member of each buckle having an eye to engage one of the fastener-members.

Signed at New York city, in the county of 95 New York and State of New York, this 18th day of July A. D. 1914.

JOHN FRANK.
